UNITED STATES PATENT OFFICE.

JOSEPH HORAT, OF LA FAYETTE, INDIANA.

COMBINED LADLE AND MOLD FOR SOFT-METAL HAMMERS.

1,095,866.

Specification of Letters Patent.

Patented May 5, 1914.

Application filed July 22, 1913. Serial No. 780,516.

To all whom it may concern:

Be it known that I, JOSEPH HORAT, a citizen of the United States, residing at La Fayette, in the county of Tippecanoe and State 5 of Indiana, have invented new and useful Improvements in Combined Ladles and Molds for Soft-Metal Hammers, of which the following is a specification.

This invention relates to combined mold 10 and ladle for use in casting hammer heads made of lead or other soft metal upon a suitable handle, the object of the invention being to provide a sectional mold of this character, the sections of which are hinged 15 for ready opening and closing movements and are adapted to be fastened in closed position for the mold operation and opened for the removal of the form head, and further to provide a mold of the character described 20 having a ladle whereby the operation of filling the mold is rendered more convenient and facilitated.

The invention consists of the features of construction, combination and arrangement 25 of parts herein fully described and claimed, reference being had to the accompanying drawing in which:—

Figure 1 is a perspective view showing the mold opened, with a handle applied in position ready for the closing of the mold and the molding of the hammer head. Fig. 2 is a similar view of the closed mold. Figs. 3 and 4 are longitudinal and transverse sections through the mold.

35 My improved mold is especially designed for the production of soft metal hammer heads 1 molded upon a suitable handle 2, which may be made of gas pipe or tube or any suitable material. In the present instance I have shown the use of a handle 40 which is longitudinally slotted at the point where it is embedded in the head and provided with oppositely bent anchoring projections 3 for an obvious purpose.

45 The mold comprises a pair of substantially companion sections 4 and 5 of a proper size and shape to produce the head 1. These sections are provided at their outer sides with interfitting knuckles 6, connected by 50 pintles or otherwise hingedly connected, to adapt said sections for opening and closing movement. The inner sides of the sections are provided with semi-circular portions 7

forming a tubular shank to accommodate and fit about the portion of the handle adjacent the end thereof which is to be embedded in the head. A collar 8 is provided to encircle said shank portions 7 and carries diametrically opposed set screws 9 to bind upon same, whereby the mold sections may 60 be held closed and the handle at the same time rigidly clamped in applied position. The mold sections have end walls 10 at one end adapted to closely abut and their opposite end walls are formed with flaring holes 65 low projections 11 producing a nozzle for the inflow of the liquid metal from a ladle 12, which may be integral with one of said nozzle sections and is provided with a pouring lip 13, whereby any excess metal may be 70 conveniently drained therefrom. When the mold sections are closed the nozzle sections 11 fit snugly together, so that the metal may be taken up in the ladle and then by tilting the handle and mold as a unit caused to 75 flow by gravity through the nozzle into the mold chamber for the formation of the head about the inclosed end of the handle. After the head has been formed, the set screws 9 may be loosened, and the collar 8 80 slipped back off the handle, thus releasing the mold which may be opened for disengagement from the form head, leaving the completed handle free. One or more vent openings 14 may be formed in the mold for 85 the escape of air during the molding operation.

From the foregoing description, it will be seen that my invention provides a mold of the character described which is simple of 90 construction, convenient of operation, and enables heads of the character described to be quickly and easily molded about the handles, and adapts the mold for ready and quick application and removal.

95 I claim:—

As a new and improved article of manufacture, a mold of the character described comprising a horizontally and longitudinally divided mold body formed of a pair 100 of mold sections hingedly connected at one side and provided with tubular shank forming portions at their opposite sides, said mold sections being further provided with complementary spout forming portions integral therewith at one end thereof, means

coöperating with said shank forming portions to hold the mold closed, and a ladle extending longitudinally at one end of the mold, said ladle being integral at its inner 5 end with one of said spout forming portions and arranged therewith to discharge into the end of the mold.

In testimony whereof I affix my signature in presence of two witnesses.

JOSEPH HORAT.
